CLAIM

The ornamental design for a computer printer, as shown and described.

DESCRIPTION

FIG. 1 is a front view of a computer printer showing a first embodiment of our new design;

FIG. 2 is a back view thereof;

FIG. 3 is top view thereof;

FIG. 4 is a bottom view thereof;

FIG. 5 is a left side view thereof;

FIG. 6 is a right side view thereof;

FIG. 7 is a perspective view thereof;

FIG. 8 is a front view of a computer printer showing a second embodiment of our new design;

FIG. 9 is a back view thereof;

FIG. 10 is top view thereof;

FIG. 11 is a bottom view thereof;

FIG. 12 is a left side view thereof;

FIG. 13 is a right side view thereof; and,

FIG. 14 is a perspective view thereof.

The broken lines depict portions of the computer printer in which the design is embodied that form no part of the claimed design; additionally, the dash-dot broken lines denote the boundary of the claimed design and form no part of the claimed design.
